UNITED STATES PATENT OFFICE.

HENRY WILLIAM BATLEY, OF WANDSWORTH, COUNTY OF SURREY, ENGLAND, ASSIGNOR TO ARNOLD, CONSTABLE & CO., OF NEW YORK, N. Y.

DESIGN FOR A RUG.

SPECIFICATION forming part of Design No. 19,396, dated November 5, 1889.

Application filed October 12, 1889. Serial No. 326,878. Term of patent 3½ years.

To all whom it may concern:

Be it known that I, HENRY WILLIAM BATLEY, a subject of the Queen of Great Britain, residing at Wandsworth, in the county of Surrey, England, have invented and produced a new and original Design for a Rug; and I do hereby declare that the photographic print accompanying this specification conveys to any one skilled in the art a clear understanding of the same, and is sufficient to enable such person to use my invention.

What I claim as my invention, and desire to secure by Letters Patent, is—

The design for a rug, consisting in the ornamentalations shown in the photographic print accompanying this specification.

HENRY WILLIAM BATLEY.
